UNITED STATES PATENT OFFICE.

JAMES WALLACE AND WILLIAM H. TAYLOR, OF PROVIDENCE, RHODE ISLAND, ASSIGNORS, BY MESNE ASSIGNMENTS, TO SAID WALLACE.

SNAP-HOOK FOR JIB-STAYS.

SPECIFICATION forming part of Letters Patent No. 768,921, dated August 30, 1904.

Application filed April 4, 1904. Serial No. 201,485. (No model.)

To all whom it may concern:

Be it known that we, JAMES WALLACE and WILLIAM H. TAYLOR, citizens of the United States of America, and residents of Providence, in the county of Providence and State of Rhode Island, have invented certain new and useful Improvements in Snap-Hooks for Jib-Stays, of which the following is a specification.

Our invention relates to improvements in snap-hooks, and more especially to snap-hooks arranged to be secured to the edge of jibs or sails and adapted to be readily attached to or detached from the jib-stays of yachts or other sailing vessels; and it consists, essentially, of the fixed or normally stationary member having a semihook or eye at one end and at the other a base portion capable of being seized to the edge or bolt-rope of the sail and a laterally-movable spring-pressed fellow member, pivoted to the shank of the fixed member, having a semihook or eye overlapping the corresponding portion of the other member and forming the complement thereof, all as will be more fully hereinafter set forth and claimed.

We are well aware that laterally-separable snap-hooks for harnesses, &c., have been devised prior to our invention. In such former snap-hooks, however, the outer end portion thereof was bent and extended circumferentially quite a distance beyond the center or eye proper, the cross-sectional area of such bent portion being materially increased in order to render the sustaining capacity of the hook approximately equal to an integral or closed eye.

The object we have in view is to provide a cheap or inexpensive snap-hook for jib-stays, the device being adapted to be readily attached to or disconnected from the stay at will. The cross-sectional area of the eye or hook portion proper is substantially uniform throughout, the ends or center portions of the members being halved or locked together and extending past each other a considerable distance in opposite directions.

Another advantage possessed by our improved snap-hook for jib-stays is that the

outer edge or bolt-rope of the sail or jib may 50 be brought nearer the stay than is possible when other devices of this class are used, thereby correspondingly increasing the sail area.

In our improved construction the direct pull 55 upon the snap-hook when in use is borne by both members, although the actual contact of the stay with the hook is practically taken by the fixed member.

We would further state that the improved 60 hook is adapted to be applied to or removed from the stay without opening the hook by hand, or, in other words, by means of a short projecting lug formed on the outer end of the movable member the latter may be readily 65 swung laterally or sidewise upon engaging the lug with the stay itself and imparting a slight twist to the corresponding portion of the sail.

In the accompanying sheet of drawings, 70 illustrating our improved snap-hook for jib-stays, Figure 1 is a top plan view of the device. Fig. 2 is a corresponding edge or side elevation. Figs. 3 and 4 are front views of the two principal members of the hook detached from each other. Figs. 5 and 6 are corresponding side views of said members, and Fig. 7 is a perspective view of the spring employed for automatically closing the hook.

In carrying out our improved snap-hook 80 A for jib-stays we employ a normally stationary member *a* and the movable or laterally-swinging member *b*, jointed at *c* to the shank portion *a'* of the former. The member *a* is also provided with an elongated integral base 85 *d*, the latter being arranged at right angles to the plane of the hook, the width of said base being equal to or slightly exceeding the combined thickness of the two shank portions *a'* and *b'*. The form of the base cross-sectionally is as drawn concavo-convex, thereby adapting it to conform to the outer or bolt-rope edge of the sail. It may be secured to the latter by seizing stuff in a well-known manner.

The outer portion *a'* of the bend or eye of the member *a* extends well past the center line *m* and is cut away or divided circumfer-

entially to form a lipped seat a^4 . The corresponding portion b^3 of the other member b is cut away circumferentially to receive the said part a^3 , the cross-sectional form of the hook at said reduced portions being circular or cylindrical and smooth. In other words, the cross-sectional area of the eye proper is substantially uniform throughout, both through the solid part and the divided portions.

The member b is provided at or near the outer end with an integral projecting lug or lip b^4 , adapted in use to engage the stay and thereby open the hook for the reception of the stay or for detaching it therefrom.

The shank a' is counterbored to receive a short helical spring s and also to receive the hub b^5 of the movable member b . One end, s^1 , of said spring is held in a recess a^5 , formed in the shank, the other end, s^2 , being held in a recess b^6 , formed in the face of said hub, a rivet or pin c , passing through the center of the joint, serving to maintain the parts in proper relation, all as clearly shown. It will be seen that the face of said shank portion a' is provided with an elongated notch a^6 , into which the end s^2 of the spring extends beyond the recess b^6 , thereby forming a stop for limiting the swinging or angular movement of the member b when the hook is opened. (See also Fig. 1.)

In Fig. 2, j indicates a stay, and r' a portion of a jib or sail having its edge bound with a bolt-rope r and having our improved snap-hook fastened thereto. The said parts j , r' , and r are indicated by dotted lines.

We claim as our invention and desire to secure by United States Letters Patent—

1. As an improved article of manufacture, the herein-described snap-hook for jib-stays, the same consisting of the normally stationary or fixed member a having an integral base or foot adapted to be secured to the edge of a jib or sail, and a spring-pressed member b pivoted to member a , the outer ends of said two members being bent and extending past each other and also cut away to form a joint or seat, substantially as set forth.

2. In a snap-hook of the class described, the combination of a relatively stationary member a bent to form a partial eye or loop, a spring-pressed member b pivoted or jointed to member a also bent to form a partial eye, the adjacent ends of said bent portions being reduced in thickness and overlapping each other and when closed forming a continuous eye, and having said member a provided with a base d , arranged at right angles to the axis of the joint-pivot, adapted to be seized to the bound edge of a sail or jib, substantially as described.

3. In a snap-hook of the class described, the combination with the main member a provided with an attaching-base, of the spring-pressed member b pivoted to said member a , the outer ends of the eye portions of each of said members being partly cut away and extending beyond each side of the median line m and in engagement with each other, substantially as described.

4. In a snap-hook of the class described, the combination of the relatively stationary member a and the spring-pressed member b pivoted to the shank of said member a , and having the free end of the movable member provided with a projecting outer lug b^4 located in the plane of the hook's eye, substantially as described and shown.

5. In a snap-hook of the class described, the combination of the relatively stationary member a having a counterbored recess formed in its shank, a helical spring s mounted and held therein, a fellow member b having its shank provided with an integral short hub movably fitted in said counterbore and retaining the other end of said spring, and a securing pin or rivet passing through the shank portion of said members and spring, substantially as described.

Signed at Providence, Rhode Island, this 2d day of April, 1904.

JAMES WALLACE.
WM. H. TAYLOR.
